UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING-MACHINE.

1,333,356.

Specification of Letters Patent.

Patented Mar. 9, 1920.

Application filed August 15, 1917. Serial No. 186,274.

To all whom it may concern:

Be it known that I, JOHN WALDHEIM, a citizen of the United States, residing in Elizabeth, in the county of Union and State of New Jersey, have invented certain new and useful Improvements in Typewriting-Machines, of which the following is a specification.

This invention relates to an improvement in typewriting machines, and more especially to key-set tabulating mechanism.

The purpose of the invention is to enable tabulating mechanism for a typewriter carriage to be rapidly and accurately set, so as to determine subsequently tabulated positions for the carriage. The carriage is provided with settable stops, one for each letter-space, and when the carriage is selectively positioned and a lever operated in one direction, a stop corresponding to that position of the carriage is set. A number of stops can be set in this way to determine a plurality of major columns or zones at which the typewriter carriage must thereafter stop. The decimal-tabulating mechanism is used to coöperate with these carriage-carried stops to position the carriage according to the pre-arranged plan.

The set stops can be unset by operating the same lever at the keyboard but in the opposite direction from setting any selected stop, after the carriage has been positioned to bring the stop into register with the setting and unsetting plate. The shifting-lever for the stop-setting means is normally held in an intermediate neutral position by means of a pair of spring-actuated counterbalanced arms.

Other features and advantages will hereinafter appear.

In the accompanying drawings,

Figure 1 is a vertical section, taken from front to rear, with parts omitted to simplify the showing, and illustrating the stop-setting and clearing lever in a neutral position.

Fig. 2 is a detail section, taken from front to rear, of the stop-setting mechanism, showing the stop-carrying bar as raised in the act of setting one of the stops.

Fig. 3 is a view similar to Fig. 2, except that the stop-carrying bar is depressed to unset a previously-set stop.

Fig. 4 is a top plan view, with the stop-carrying bar broken away to show the position of the plunger stops beneath the same.

Fig. 5 is a vertical, detail section of a modified form of stop-carrying bar, which can be operated from the carriage instead of from the keyboard, as in the case of the form shown in the remaining figures.

Numeral keys 1 and alphabet keys 2 depress key levers 3, to rock bell-crank 4, so as to swing type-bars 5 up rearwardly against the front side of a platen 6 mounted to rotate on a carriage 7. The carriage 7 has the usual step-by-step movements when the numeral keys and character keys 1 and 2 are actuated, under the control of an escapement mechanism indicated in general at 8. This escapement mechanism includes a rack bar 9 supported by the carriage 7 by means of arms 10. The rack bar 9 normally engages a pinion 11 connected by a one-way pawl-and-ratchet mechanism (not shown) to an escapement wheel 12. The wheel 12 is controlled by a pair of fixed and loose dogs 13 and 14, which are operated by a universal frame 15. The universal frame 15 is connected to a universal bar 16, which lies in the path of heels 17 carried by the type-bars 5. This escapement mechanism is the usual Underwood typewriter escapement mechanism, and acts at the striking of the character keys to control the advancing step-by-step movements of the carriage 7 as it is drawn by the usual spring barrel 18.

In addition to the step-by-step movements, the carriage 7 may have major or jump movements under the control of a tabulating mechanism. This tabulating mechanism includes a plurality of decimal-tabulating keys 19, one for each decimal column within the capacity of a zone or major column. The tabulating keys 19, when depressed, rock key levers 20 to raise at their rear ends plungers 21. The plungers 21, when thrust individually in this way, come into the path of the set stops of a series 22 carried by the carriage 7.

The typewriter carriage 7 is released by the tabulating keys 19 as they are depressed, so as to permit the spring barrel 18 to draw the carriage until the next one of the stops 22, which happens to be set, is obstructed in its movement by the particular plunger 21 projected. To do this, each of the plungers 21 is provided with a ledge or shoulder 23 formed by a notch cut out of the associated plunger. These shoulders underlie an arm 110

24, universal to all of the plungers 21 and forming part of a lever 25. When any of the tabulating keys 19 is depressed to move its plunger 21 to an obstructing position, 5 the lever 25 is rocked so as to draw down on a link 26, and thus rock a lever 27 pivoted intermediate its ends. The lever 27 carries at its forward end a roller 28 underlying the rack 9 and acting to raise the rack 10 9 out of mesh with the pinion 11. In this way, the carriage is released to permit it to jump forward until obstructed by an engagement of the next carriage-carried stop 22 and the particular plunger 21 projected. 15 Thus the carriage can be successively positioned to a plurality of pre-arranged zones or major columns and to a selected decimal column in each zone.

Mechanism is provided for the purpose of 20 rapidly setting the stops 22, so as to obtain a pre-arranged selection of zonal positions and decimal-column selections in the zones. This includes a stop bar or rail 29, which carries the stops 22, and, in turn, may be 25 carried by the carriage 7. There is one of the stops 22 for each letter-space within the capacity of the carriage 7, and only such stops as are to be used are set at any particular time. The stops 22 extend vertically 30 through slots 30 provided in the rail 29, and have projections 31 and 32 extending over and under the bar 29, so as to limit the up-and-down movement of the stops 22 relative to the bar 29. The stops 22 have two positions, one raised and inactive, and the other depressed and active. The stops are locked in these positions by spring-pressed 35 balls 33.

The rail 29 is mounted on a swinging 40 frame 34, which is pivoted on the carriage 7, and may move from an intermediate position to either a depressed position, shown in Fig. 3, or a raised position, shown in Fig. 2. In the raised position shown in Fig. 2, 45 the particular stop 22, corresponding to the position of the carriage 7, will be set. In the depressed position illustrated in Fig. 3, a previously-set stop, corresponding to the position of the carriage, will be unset. The 50 setting and unsetting of the stops 22 are accomplished by a fixed plate 35, which is provided with an upper arm 36 extending above the row of stops 22, and a lower arm 37 extending below the row of stops 22. The 55 plate 35 is located just to the left (Fig. 4) of the series of plungers 21, or, in other words, just to the left of the plunger which determines the decimal-point position of the carriage for any particular zone. 60 The shifting of the frame 34 and thus of the rail 29, is controlled, in the form shown in Figs. 1 to 4, by a hand-lever 38 located at the front of the machine adjacent the bank of character keys 1 and 2. Normally, 65 the hand-lever 38 occupies the neutral posi-

tion shown in full lines in Fig. 1, but it may be shifted alternatively to either the setting position or the clearing position, indicated in dotted lines in Fig. 1. When shifted to the setting position, the hand-lever 38 draws 70 on a link 39 to rock a bell-crank 40. The bell-crank 40 draws on a link 41, so as to rock downwardly and forwardly a shifter 42. This shifter 42 is provided with a cam slot 43 having several cam surfaces, one set 75 46^a serving to normally lock the stop-bar 22 against movement, being for this purpose formed as arcs struck from the pivot 42^a of the shifter 42, and therefore being dwells. Another pair of these cam surfaces, indicated particularly at 44, act, when the shifter 42 is swung downwardly and forwardly in this manner, to thrust upwardly and forwardly on a rod 45 extending through the cam slot 43 and located on the 85 swinging frame 34. This swings the rail 29 upwardly to force the particular stop 22, located in register with the setting plate 35, against the upper arm 36 thereof. As this arm is stationary, it will cause the particular stop in question to be depressed below its fellows.

The shifter 42 is also provided with a pair of opposed cam surfaces 46 bordering the slot 46^a, which, when the lever 38 is forced 90 to the position marked "clear" in Fig. 1, swings the frame 34 downwardly (Fig. 3), so as to bring a previously-set stop, which corresponds to the position of the carriage, against the lower arm 37 of the plate 35. 100 This will cause the stop to move up relatively to the rail 29, and, when the rail 29 is returned to a normal position, it will be in an unset position. The lever 38 and the parts shifted thereby are held in a normally 105 intermediate position by means of counter-acting spring-actuated mechanism. This includes a block 47 secured to the link 39 and engaged on opposite sides by a pair of arms 48 and 49 pivoted at 50 and 51. The 110 inward movement of the arms 48 and 49 toward each other is limited by a stop 52. The arms 48 and 49 are held against the stop 52 by means of springs 53 and 54.

The operation of this form of the device 115 so far described will be readily understood when taken in connection with the above description. For the purpose of illustration, the series of stops 22 may all be assumed to be unset. The carriage 7 may then be positioned by the usual scale and pointer to the particular location desired for the first major column or zone and for the decimal-point column in that zone. This will bring the stop 22 for that zone in register with the 120 setting and unsetting plate 35. The lever 38 may be shifted to the "set" position illustrated in dotted lines in Fig. 1, whereby the frame 34 will be rocked forwardly and upwardly, so as to raise the rail 29 and carry 125 130

the particular stop 22, corresponding to the zone or major column selected, up against the overhanging arm 36. The further movement of the stop 22 is obstructed while 5 the rail 29 continues its movement, thus causing the stop to be displaced downwardly relatively to the rail 29 to a set position. The hand-lever 38 is then shifted to an intermediate neutral position by the 10 spring 54, and the carriage 7 advanced to the decimal point in the next major column or zone desired. Then the lever 38 is again shifted to the set position to adjust the selected stop 22 to a set position. The operation 15 is repeated for each zone or major column within the range or capacity of the carriage 7. When the carriage-carried stops 22 have been set according to the desired plan, the particular work for which the 20 same were set can be done.

For each line of writing, the carriage starts at the right and one of the decimal-tabulating keys 19 is depressed according to what particular decimal column in the first 25 zone is desired. The depression of this decimal-tabulating key releases the carriage, so that it starts to jump forward until the associated plunger 21, which has been projected, obstructs the movement of the first 30 set stop 22 on the carriage 7. At the rise of the tabulating key, the carriage, as is usual, steps forward a letter-space, or nearly a letter-space, until it is arrested at the desired point by the loose dog 14. It is to 35 allow for this step forward that the setting plate 35 is set to the left of the decimal plunger 21. This is repeated for each zone or major column, selecting, if desired, different decimal columns in each zone by 40 operating the proper tabulating key 19.

For a change in the setting of the stops 22 for some other kind of work, the carriage 7 is positioned, by the assistance of the decimal key of the tabulator keys 19, to 45 bring each set stop individually into register with the plate 35, and the lever 38 is shifted to the "clear" position illustrated in Fig. 1, so as to rock the stop-carrying bar 29 downwardly, thus forcing the set stop to an unset 50 position.

A modified form of device is shown in Fig. 5, in which the stop-carrying rail 29 is more directly operated from a point adjacent the carriage 7. In this case, the stop-carrying rail 29 is mounted on a frame 55, which, in turn, is pivotally mounted at 56 on the carriage 7. This frame is provided with an arm 57 extending upwardly to a projecting position above the carriage 7 and 60 located at one side thereof. The arm 57 is normally held in a neutral position by means of a pair of springs 58 extending on opposite sides of pins 60 and 61, located, respectively, on the arm 57 and the carriage 7.

The arm 57 is provided with a handle 62,

whereby it may be shifted from a neutral position to either set position, whereby the stop rail 29 can be shifted either up or down to set or unset the stops 22. A plate 63, similar to the plate 35, is provided with an 70 overhanging arm 64 and an underlying arm 65, so as to set or unset the stops 22 according to the manner in which the rail 29 is shifted. The operation of this form is the same in a general way as the form illustrated in the other figures, and the stops 22 are set in a similar manner, the only difference being that the operating handle is carried by the typewriter carriage, and, therefore, the rail 29 is more directly 80 operated.

Variations may be resorted to within the scope of the invention, and portions of the improvements may be used without others.

Having thus described my invention, I claim:

1. The combination with a typewriting machine including a carriage, of a stop-rail mounted on said carriage, a series of stops adjustably mounted on said rail so as to 90 be movable between set and unset positions, a setting plate adjacent said rail and said stops, and means for shifting said rail to bring individual ones of said stops against said setting plate, so as to set or unset said 95 stops one at a time.

2. The combination with a typewriter carriage, of a swinging frame pivotally mounted on said carriage, a series of settable stops mounted on said swinging frame, a 100 shifter having a cam contour to adjust said frame between a neutral position and setting and unsetting positions, a setting plate located in the range of swinging movement of said stops, and means for shifting said frame to bring the stops into engagement with said setting plate for the purpose of setting and unsetting said stops.

3. The combination with a typewriting machine including a carriage, of a rail 110 adapted to be swung on said carriage, a series of stops on said rail settable from inactive to active positions, a stationary setting plate extending on opposite sides of said rail, so as to set and unset individual stops, 115 and means for shifting said rail alternatively in different directions to engage individual stops with said plate, so as to set and unset said stops one at a time.

4. The combination with a carriage, of a 120 frame pivotally mounted on said carriage, a rail carried by said frame, a series of stops settable on said rail between active and inactive positions, a setting plate encompassing said rail for a space of one stop, a cam- 125 shifter for moving said frame to bring individuals of said stops into engagement with said plate, and means for operating said shifter.

5. The combination with a carriage, of a 130

frame movably mounted on said carriage, a stop-rail carried by said frame, a series of stops mounted on said rail, and movable with said rail and said frame, a fixed member lying in the path of movement of said stops relative to said carriage, and a shifting member having a plurality of cams to adjust said frame selectively in different directions, for the purpose of selectively setting and unsetting said stops.

6. The combination with a carriage, of a stop-rail mounted on said carriage, normally occupying an intermediate position and movable alternatively in opposite directions, a series of stops carried by said rail, and adjustable relatively thereto, for the purpose of being set from inactive to active positions, fixed means lying in the path of individuals of said stops when said rail and said stops are swung to set and unset said stops, and shifting means for moving said rail alternatively in opposite directions, including a rod and a plurality of pairs of cams for positively moving said rail in opposite directions from an intermediate neutral position.

7. The combination with a carriage, of a stop-rail mounted on said carriage, normally occupying an intermediate position and movable alternatively in opposite directions, a series of stops carried by said rail, and adjustable relatively thereto, for the purpose of being set from inactive to active positions, fixed means lying in the path of individuals of said stops when said rail and said stops are swung to set and unset said stops, shifting means for moving said rail alternatively in opposite directions, including a rod connected to said rail and a plurality of pairs of cams engaging said rod for positively moving said rail in opposite directions from an intermediate neutral position, and spring means for yieldingly holding said shifting means in an intermediate normal position.

8. The combination with a carriage, of a series of stops for determining jump movements of said carriage, a rail on which said stops are adjustably mounted between inactive and active positions, a fixed plate having arms extending on opposite sides of said rail and said series of stops, so as to lie in the path of movement of said stops when swung in one direction or the other to set and unset the same, shifting means for moving said rail and said stops alternatively in opposite directions, and counterbalancing springs for yieldingly holding said shifting means in a normal intermediate position, in which position said stops will clear both arms of said plate.

9. The combination with a carriage, of a series of stops for determining zonal positions of said carriage; means for setting said stops between active and inactive posi-

tions, including a lever shiftable from a neutral position to either one of two active positions and a link operated by said lever, and means for holding said setting means in an intermediate neutral position, including a block secured to said link, a pair of opposing arms engaging said block on opposite sides, a spring for each of said arms, and a stop interposed between said arms for determining the normal intermediate position of said arms and said lever.

10. The combination with a traveling carriage, of a pivoted stop bar on said carriage, settable stops on said bar, and controlling means for said bar normally effective to lock the same against turning on its pivot, said controlling means including means for swinging said bar on its pivot to effectively set said stops.

11. The combination with a supporting frame and a traveling carriage, of a pivoted stop bar on said carriage, settable stops on said bar, and a controlling mechanism mounted in said frame and normally effective to lock the same against turning on its pivot, said controlling mechanism including means for swinging said bar on its pivot to effectively set said stops.

12. The combination with a traveling carriage, of a pivoted stop bar on said carriage, stops on said bar movable transversely relatively thereto, movement-controlling means for swinging said stop bar on its pivot, and an obstruction which may be in the transverse path of any one of said stops, depending upon the position of said carriage, so that the movement-controlling means, when operated to swing said stop bar, will be effective to either set or unset the stop, the path of which is intercepted by said obstruction, said movement-controlling means including means normally effective to lock said stop bar against turning on its pivot.

13. The combination with a traveling carriage, of a pivoted stop bar on said carriage, settable stops on said stop bar, an actuator for said stop bar, means for holding said actuator in a neutral position, and means for locking said stop bar against actuation when said actuator is in its neutral position.

14. The combination with a traveling carriage, of a frame pivotally supported on said carriage, a stop-carrying rail mounted on said frame to move therewith, both with the travel of said carriage and with the setting movements of said frame, a series of stops carried by said rail, traveling with said rail and swinging with said rail to be set or unset, a shifter pivotally mounted near said rail, having a cam slot therein, a rod on said frame extending through said cam slot to enable the shifting of said rail and said stops, so as to set and unset said

stops, and a member located in the path of shifting movement of said stops, so as to adjust them relatively to said rail by obstructing their movement.

- 5 15. The combination with a traveling carriage, of a frame having a pivotal mounting on said carriage, a stop-rail secured to said frame in spaced relation with the axis of said pivotal mounting on said carriage, a 10 series of stops on said rail settable between effective and ineffective positions, a plate extending on opposite sides of said rail and said stops to set and unset the latter by obstructing the movement thereof, shifting 15 means for said frame and said rail, pivoted in the rear of said rail and extending between said rail and said pivotal axis of said frame on said carriage, and contacting with said frame, so as to shift the same to set said 20 stops, and means connected to said shifter

at a point in front of said rail to operate the same.

16. In a typewriting machine, the combination with a machine frame and a typewriter carriage mounted for movement thereon, of a rack-bar pivoted on the carriage, a series of stops slidably mounted on said bar, a fixed lug against which said stops may be selectively swung by swinging said bar on its pivot to slide a stop to active position, a keyboard forming part of the typewriter, and a mechanism mounted in said machine frame and controlled by a key convenient to said keyboard adapted to swing said rack-bar to set a stop thereon. 30 35
